UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

COMBINED COVER-SLIDE AND EDGE-GUIDE.

1,323,355.

Specification of Letters Patent.

Patented Dec. 2, 1919.

Application filed February 17, 1917. Serial No. 149,370.

To all whom it may concern:

Be it known that I, ALBERT H. DE VOE, a citizen of the United States, residing at Westfield, in the county of Union and State 5 of New Jersey, have invented certain new and useful Improvements in Combined Cover-Slide and Edge-Guide, of which the following is a specification, reference being had therein to the accompanying drawings.

This invention relates to sewing machines and particularly to attachments for the cloth-plate thereof.

It has for its object to improve the construction disclosed in my copending application Serial No. 120,443, filed September 16, 1916, to enable an edge-guide carried by a slide-plate being set, within certain limits, to any one of several positions at predetermined distances from the needle thereby avoiding strain of the operator's vision which is frequently involved in the use of scales or similar devices commonly employed for this purpose.

25 A further object of the invention is the provision of a locking device for holding a cover-slide in guideways so that by a single application of force in the direction it is desired to move the slide-plate the same 30 may be first unlocked and moved substantially simultaneously with a little or no effort in a corresponding direction.

For accomplishing these results, the construction of the application mentioned has 35 been modified by substituting for the cam-lever a latching mechanism comprising fixed and movable elements attached to the cloth-plate and cover-slide, respectively. The movable element, preferably in the form 40 of a lever, is formed with a projection or latch proper normally spring-pressed into engagement with the fixed element, preferably in the form of a rack, teeth being provided on the contiguous edges of both elements to lock the cover-slide against movement in the guideways. The lever is mounted for movement about either of two fulcrum studs on the cover-slide so that it may 45 be moved lengthwise in a direction toward or from the needle by exerting pressure on the finger portion of the lever in a corresponding direction.

The invention consists further in certain features of construction which will appear 55 in the following detailed description of the

accompanying drawings, in which Figure 1 is a plan view and Fig. 2 a vertical section on line X—X', Fig. 1, of the preferred embodiment of my invention.

The cloth-plate 1 has a raised portion 2 in 60 which is provided an opening indicated generally at 3 bridged by a throat-plate 4 of suitable form having an elongated needle-hole 5 therein through which a needle 5' is adapted to be reciprocated by any suitable 65 mechanism. Cover-plates 6 and 7 are arranged flush with and on opposite sides of the throat-plate and their edges 8 and 9 are beveled to fit undercut guideways 10 formed along the sides of the opening 3 in the 70 cloth-plate. The cover-plate 7 is recessed in its bottom face as indicated in dotted lines at 11, Fig. 1, to receive the body or shank 12 of an edge-guide, the active fabric-engaging portion 13 of which extends 75 at substantially right angles to the body or shank upward through a slot 14 in the cover-slide and forward over the throat-plate 4 into close proximity with the needle 5'. For adjusting the edge-guide on the 80 cover-plate 7 the latter is formed with a slot 15 receiving a clamp-screw 16 tapped into the body or shank 12. The foregoing construction is substantially the same as that shown and described in the above mentioned 85 application and the specific construction forms no part of the present invention.

A locking mechanism is provided for holding the cover-slide in any one of several positions, so that the edge-guide may be 90 located a known distance from the needle-path when the character of the work renders it desirable to quickly change the distance of the stitching from the edge of the body-fabric being operated upon. A rack 20 having teeth 21 of any suitable size is secured to the cloth-plate 2 along the sides of the guideways in a recess 22 by screws 23 which pass through slots 24 in the rack, thereby affording a facility for adjustment of the latter. 95 Coöoperating with the rack is a lever 25 movably mounted on the cover-slide 7 and having a projection or detent 28, constituting the latch proper, equipped with a suitable number of teeth 29 of suitable size which 100 teeth are normally held in engagement with those on the rack by a spring 30 coiled about a pin 31 carried by a block 32 arranged internally of the lever (when viewed as in Fig. 1), the block affording a fixed abutment 105

for one end of the spring 30 which at its opposite end impinges against a seat 33 on the lever. The lever 25 is cut out as indicated on the drawing, the side walls 34 and 35 of the incision being inclined to the base 36, and the block 32 screwed at 32' to the cover-slide within the substantially triangular shaped incision limits the rocking movement of the lever about either of the fulcrum-pins 37 embraced by the slots 38 formed in the lever adjacent the projection or latch after the latter has been disengaged from the rack. The slots 38 may be of any suitable form and length it being essential only that they permit the rocking movement of the lever about either fulcrum-pin sufficient to disengage the teeth on the latch from those on the rack. As shown, the slots are open-ended and the walls defining the same are respectively concentric to the opposite fulcrum-pin, being also spaced apart approximately the diameter of a pin. Preferably these pins 37 are provided with heads 37' which in conjunction with the wing 32" carried by the block hold the lever flat against the cover-slide. Preferably also, but not necessarily, the fulcrum-pins and slots are so constructed and arranged that they limit the bodily movement of the lever and latch across the guideways and consequently limit the depth of engagement of the teeth on the latch and rack thereby eliminating the possibility of a locking or jamming of the teeth when the rocking movement of the lever is initiated.

While the construction of the latch is especially useful in the relation shown and described it is to be observed that said latch may be used in other relations where a sliding member or plate is fitted to guideways and quick rapid definite adjustment is a desideratum.

To move the edge-guide to the right as shown in Fig. 1 the lever 25 is pressed to the right, which causes the lever to swing about the right-hand fulcrum-pin 37 as a pivot and frees the teeth 29 from the rack. The cover-slide 7 now being released, continued pressure on lever 25 causes the plate to move to the right. On releasing the lever the spring 30 immediately presses the teeth 29 into engagement with the rack and locks the cover-plate in adjusted position. To move the cover-plate in the opposite direction the lever 25 is operated in the reverse manner. Because the teeth may be made as small or as large as desired the distances that the edge-guide is located away from the needle, which is predetermined by the size of the teeth, may be selected to suit the requirements of the work. By the particular double fulcrum arrangement for the latch-lever 25 the edge-guide may be located with quickness and ease.

Having thus set forth the nature of the invention, what I claim herein is:—

1. In a sewing machine, in combination, a member provided with guideways, a plate fitted to said guideways for movement therein, devices on said member and plate respectively normally engaged to lock the plate against movement, and means manually movable by the application of force in either of two opposite directions to unlock and slide the plate in said guideways in a corresponding direction. 65 70 75

2. In a sewing machine, in combination, a member provided with guideways, a plate fitted to said guideways for movement therein, devices on said member and plate respectively normally engaged to lock the plate against movement, and means manually movable by the application of force in either of two opposite directions to unlock and slide the plate in said guideways in the corresponding direction, said means including a lever movable in opposition to a spring. 80 85

3. In a sewing machine, in combination, a member provided with guideways, a plate fitted to said guideways for movement therein, devices on said member and plate respectively normally engaged to lock the plate against movement, means movable by the application of force in either of two directions to unlock and slide the plate in said guideways in a corresponding direction, said means including two fulcrum-pins and a lever arranged for rocking movement about either of the pins. 90 95

4. In a sewing machine, a cloth-plate provided with guideways, in combination with a cover-slide fitted to said guideways, and coacting locking devices on said plate and slide for holding the cover-slide in different positions against lengthwise movement in either direction, one of said devices forming means for moving the slide in either direction. 100 105

5. In a sewing machine, a cloth-plate provided with guideways, in combination with a cover-slide fitted to said guideways, and coacting locking elements on said cloth-plate and cover-slide for holding the latter against lengthwise movement in either direction, one of said elements being fixed adjustably to the cloth-plate and a mating element mounted on the cover-slide for movement in either of two intersecting paths, means for normally holding said elements in engagement, and means for moving said mating element in either of said paths. 110 115 120

6. In a sewing machine having a needle, a cloth-plate provided with guideways, in combination with a cover-slide fitted to said guideways, an edge-guide carried by said cover-slide, and devices for locking said cover-slide against movement in either direction manually operable to hold the edge- 125

guide in selected positions, a predetermined distance from the needle.

7. In a sewing machine having a needle, in combination, a slide-plate, an edge-guide thereon, and mechanism for holding said slide-plate against movement in either direction, including, a fixed element, and a movable element mounted on said slide-plate, and means for adjusting said movable element relative to said fixed element to position the edge-guide in any one of a plurality of positions at predetermined distances from the needle.

8. In a sewing machine having guideways and a slide-plate fitted thereto, in combination, a toothed rack fixed parallel to said guideways, a lever having a toothed latch adapted to engage said toothed rack, two fulcrum-pins, means normally urging said lever in a direction to engage the latch with said rack, said lever being movable about either of said fulcrum-pins to disengage the latch and rack and permit movement of the slide-plate.

9. In a sewing machine having guideways and a slide-plate fitted thereto, in combination, an adjustable toothed rack fixed parallel to said guideways, a lever having a toothed latch adapted to engage said rack, a spring normally urging said lever in a direction to engage the latch with said rack, two fulcrum-pins, said lever being movable about either of said fulcrum-pins to disengage the latch and rack and permit movement of the slide-plate.

10. In a sewing machine provided with guideways and a slide-plate fitted thereto, in combination, a rack arranged parallel to said guideways and having teeth, a lever, a latch connected with said lever, said latch having teeth similar to those on the rack, a spring urging said lever in a direction across said guideways to thereby engage said latch and rack, and means limiting the movement of said lever across the guideway, said lever being movable in opposition to said spring to permit movement of the cover-slide in either direction.

11. In a sewing machine provided with

guideways and a slide-plate fitted thereto, a rack, a latch normally engaged with said rack for locking said slide-plate against movement in either direction, said lever being movable in a plane parallel to said slide-plate about either of two fulcrua to disengage said latch and rack and permit movement of the slide-plate, and means limiting the movement of said lever after the disengagement mentioned so that continued application of force on the lever in the same direction will move the slide-plate in the guideways.

12. In a sewing machine having guideways and a slide-plate fitted thereto, in combination, a fixed rack, a latch adapted to engage said rack, a lever connected to the latch and provided with a recess, a fixed abutment located within the outlines of said recess, a spring tensioned between said abutment and said lever for moving said lever to effect an engagement of said latch and rack to lock the slide-plate against movement in either direction, and means permitting said lever to be rocked in either direction against the tension of said spring, said means including devices for limiting the depth of engagement of the teeth on the rack and latch.

13. In a sewing machine provided with guideways and a slide-plate fitted thereto, a rack, a lever having a projection or latch adapted to engage said rack, a spring for normally holding said latch and rack in engagement and two fulcrum-pins symmetrically disposed on opposite sides of the line in which the spring normally functions whereby the lever may be rocked in either direction to disengage the latch from the rack.

14. In combination, a cloth-plate, a cover-slide fitted thereto, a fixed locking means on said cloth-plate, and a second locking means on said slide, said slide being unlocked and moved in either of two directions by pressure on its locking means in the desired direction.

In testimony whereof, I have signed my name to this specification.

ALBERT H. DE VOE.
